PORTABLE COMBINATION TABLE AND
TOURIST CASE

Robert L. Hestes, Pyote, Tex.

Application September 28, 1937, Serial No. 166,209

5 Claims. (Cl. 190—11)

This invention relates to a convertible structure more particularly to a combination case and table and is designed primarily for use of tourists, campers, picnickers, salesmen, but it is to be understood that a convertible structure, in accordance with this invention is for use in any connection for which it may be found applicable.

The invention has for its object to provide in a manner as hereinafter set forth, a foldable and extendible structure providing, when folded a container functioning as a portable case for the storage of wearing apparel or other articles of merchandise and, when extended providing a table upon which the contents of the case may be arranged.

A further object of the invention is to provide, in a manner as hereinafter set forth, a foldable and extendible structure providing, when folded a portable case or container for the reception of various articles of food to constitute a luncheon and, when extended providing a table upon which the luncheon may be arranged.

A further object of the invention is to provide, in a manner as hereinafter set forth a foldable and extendible structure providing, when folded a portable case for the storage of articles of merchandise to be subsequently displayed and sold by a salesman and, when extended providing a flat supported table top upon which the articles, to be sold are arranged on and displayed.

Further objects of the invention are to provide, in a manner as hereinafter set forth, a convertible structure for the purpose referred to which is simple in its construction and arrangement, strong, durable, compact when folded, expeditiously extended and folded when required, thoroughly efficient in its use, readily set up, and comparatively inexpensive to manufacture.

To the above ends essentially and to others which may hereinafter appear, the invention consists of the novel construction, combination and arrangement of parts as will be more specifically described and as illustrated in the accompanying drawings wherein is shown an embodiment of the invention, but it is to be understood that changes, variations and modifications may be resorted to which fall within the scope of the invention.

In the drawings:

Figure 1 is a perspective view of the structure when folded,

Figure 2 is a top plan view of the structure when extended,

Figure 3 is an inverted plan view of the structure when folded and further illustrating the

bracing element for the hinged sections of the table top in active position in dotted lines,

Figure 4 is an end elevation, broken away of the structure when partly extended,

Figure 5 is a side elevation, broken away of the structure when partly extended,

Figure 6 is a section on line 6—6 Figure 4,

Figure 7 is a section on line 7—7 Figure 1,

Figure 8 is a section on line 8—8 Figure 5,

Figure 9 is a section on line 9—9 Figure 4,

Figure 10 is a top plan view of the parts shown in Figure 9,

Figure 11 is a section on line 11—11 Figure 1,

Figure 12 is a section on line 12—12 Figure 4, and

Figure 13 is a section on line 13—13 Figure 1 with the side members omitted.

The structure generally indicated at 14 includes a rectangular member 15 which functions as the bottom of the case when the structure is folded and as the stationary central section of a table top when the structure is extended, a rectangular member 16 of the same length as and of greater width than the member 15, and which functions as one side of a table top when the structure is folded and as one of the hinged sections of the table top when the structure is extended, a member 17 corresponding in size to that of member 16 and which functions as the other side of the case when the structure is folded and as the other hinged section of the table top when the structure is extended, a rectangular member 18 corresponding in length to the width of the member 16 or 17 and corresponding in width to the member 15 and which functions as one end of the case when the structure is folded and also acts when the structure is extended as a filler for one of the table top's supporting legs to be referred to, a rectangular member 19 corresponding in size to member 18 and which functions as the other end of the case when the structure is folded and also acts when the structure is extended as a filler for the other table top's supporting leg, to be referred to, and a pair of supporting legs 20, 21 for the table top when the structure is extended and which also functions as a means for maintaining the sides and ends of the case in abutting relation when the structure is in a folded position.

The members 15 to 21 both inclusive, are constructed of any suitable material of the desired rigidity and thickness. The member 15 is formed at its sides with reinforcements 22, 23 which are so formed to overlap the side edges of such members. The reinforcements are fixedly secured to the member 15 by the holdfast devices and are

oppositely disposed and each of which is of U-shaped contour in transverse cross section. The reinforcements project laterally with respect to the side edges of the member 15 and spaced portions of the bend of each of said reinforcements are cut away to form what may be termed barrels and to provide a hinge member. The barrels and the cut-out portions of the reinforcements 22, 23 are indicated at 25, 26 respectively. The cut-outs and barrels may be of any suitable length. The member 15 at its ends is provided with oppositely disposed reinforcements 27, 28 which are of the same form and material but of less length than the reinforcements 22, 23. The end reinforcements 27, 28 are overlapped by the ends of the reinforcements 22, 23. The reinforcements 27, 28 are anchored to the member 15 by the holdfast means 29. The cut-outs and barrels of the reinforcements 27, 28 are indicated at 30, 31 respectively. The reinforcements 27, 28 project laterally with respect to the end edges of the member 15 and constitute hinge members.

The members 16 and 17 have their end edges overlapped by metallic reinforcements 32 anchored in position by the holdfast means 33. The inner side of the member 16 is overlapped by a metallic reinforcement 34 of the same form and arrangement as the reinforcement 22 with this exception that the cut-outs and barrels of the reinforcement 34 are alternately disposed with respect to the cut-outs and barrels of the reinforcement 22. The reinforcement 34 is anchored to member 16 by the holdfast means 35 and constitutes a hinge member. The barrels and cut-outs of reinforcement 34 are indicated at 36, 37 respectively. The barrels 37 extend into the cut-outs of the reinforcements 22 and the barrels of the latter extend into the cut-outs of the reinforcement 34. The inner side of the member 17 is overlapped by metallic reinforcement 38 of the same form and arrangement as the reinforcement 23 with this exception that the cut-outs and barrels of the reinforcement 38 are alternately disposed with respect to the cut-outs and barrels of the reinforcement 23. The reinforcement 36 is anchored to the member 17 by holdfast means 39 and constitutes a hinge member. The barrels and cut-outs of reinforcement 38 are indicated at 40 and 41 respectively. The barrels 40 extend into the cut-outs of the reinforcements 23 and the barrels of the latter extend into the cut-outs of the reinforcement 38.

The reinforcements 22, 23 extend beyond the ends of the member 15 and also beyond the ends of the reinforcements 34, 38. The barrels of the reinforcements 22, 23 are aligned respectively with the barrels of the reinforcements 34, 38. Extending through the aligned barrels of the reinforcements 22, 34 is a pintle 42 for pivotally connecting member 16 to member 15. Extending through the aligned barrels of the reinforcements 23, 38 is a pintle 43 for connecting member 17 to member 15.

The members 18, 19 are of like form and each has each side marginal portion of its inner face mortised as at 44, 45 and each side provided with a reinforcement of angle-shape cross section. The reinforcements are indicated at 46, 47 and coact with the rabbets 44, 45 to provide pockets 48, 49 respectively. The members 18, 19 are of greater thickness than the members 16 and 17 and when the structure is folded the ends of the members 18, 19 extend in the pockets 46, 47. The member 18 has secured to its inner end a laterally extended reinforcement 50 constituting a hinge

member formed with barrels 51 which align with the barrels 31 of the reinforcement 28 and extending through the aligned barrels 31, 51 is a pintle 52 which projects in opposite directions from the reinforcement 50 and pivotally connects the latter to reinforcement 28. The member 19 has secured to its inner end a laterally extending reinforcement 53 constituting a hinge member formed with barrels 54 which align with the barrels 31 of the reinforcement 27 and extending through the aligned barrels 31, 54 is a pintle 55 which projects in opposite directions from the reinforcement 53 and pivotally connects the latter to the reinforcement 27.

The pintles 52, 55 are positioned in outwardly extended relation with respect to the end edges of the members 16, 17.

The leg 20 is of inverted U-shape and includes a pair of side parts 56 and a coupling or foot part 57 merging at its ends into one end of each of the side parts 56. The other end of each of the side parts 56 is apertured as at 58 for the pivotally mounting of said ends on the pintle 52 adjacent the reinforcement 50. The leg 21 is of inverted U-shape and includes a pair of side parts 59 and a coupling or foot part 60 merging at its ends into one end of each of the side parts 59. The other end of each of the side parts 59 is apertured as at 61 for the pivotally mounting of said ends on the pintle 55 adjacent to the reinforcement 53. The legs 20, 21 are formed of strap-like material of the desired width and thickness. The ends of the pintles 52, 55 are upset to retain the legs 20, 21 respectively thereon.

The side parts 56 of leg 20 are provided on their top edges between their transverse medians and their pivoted ends with keepers 62. The side parts 59 of the leg 21 are provided on their top edges, between their transverse medians and their pivoted ends with keepers 63. The side parts 56 of the leg 20, between the keepers 62 and coupling part 57 are outset as at 64 to form transverse grooves 65 for the passage of a portion of each of the side parts 59 of the leg 21 whereby the legs 20, 21 are permanently slidably connected together. The outset parts 64 also act as retainers to prevent the side parts 59 of the leg 21 from bending outwardly relative to the side parts 56 of the leg 20 when the legs are shifted to and from table top supporting position and when in such position.

The members 18, 19 have secured to their outer faces adjacent their outer ends a pair of oppositely disposed latches 66a and have their outer faces formed centrally and lengthwise thereof with recesses 66 (Figure 11) and with resilient latching members 68, 69 respectively of strap-like form having the major portion of their length aligning with the recesses. The remaining portion of the length of the latching members, which is the inner part of these latter are anchored to the members 18, 19. The latching members 68, 69 are capable of being depressed into the recesses for the purpose of releasing those parts of the structure which they are to latch. The latching members 68, 69 intermediate their ends are formed with shoulders 70 (Figure 11). The latching members 68, 69 are employed for latching the legs 20, 21 in non-extended position when the structure is folded and with reference to Figure 1 it illustrates the structure folded with the coupling part 57 of the leg 20 seated on shoulder 70 of latching member 68 and to Figure 11 which shows the leg 21 in non-extended position, the coupling part 60 of leg 21 seated on the shoulder 75.

70 of latching member 69. When the structure is folded one of the side parts of the legs 20, 21 extends diagonally of member 16, the other side part of the legs 20, 21 extends diagonally of member 17 and the coupling parts 57 of the legs extend transversely of members 18, 19. When the legs are not extended they function as a means for retaining the members 16, 17, 18 and 19 in case forming position.

10 When the structure is extended the members 18, 19 are shifted to a position between the side parts of the legs 21, 20 respectively. When in such position, the latches 65a on member 18 engage with the keepers 63 on the side parts of leg 21 and the grooves 65 engage the side parts of leg 21, (Figure 4) whereby the upper portions of the legs, when the legs are extended are reinforced by the members 18, 19 which act as fillers.

The structure includes a shiftable bracing element 71 for the members 16, 17 when the latter are in table top forming position as shown in Figure 2. The element 71 consists of a rectangular frame 72 and a disc 73 which is arranged within, centrally of and fixed to the frame 72. 25 The element 71 is arranged below member 15 and disc 73 axially thereof is pivotally connected to member 15, as at 74. The connection is of such form that when element 71 is in inactive position it may be adjusted to tightly clamp it against the bottom of member 15 against movement. 30 When element 71 is in active position it is shifted from the full line shown in Figure 3 to the dotted line shown in Figures 2 and 3 to below members 16, 17. Prior to shifting element 71 to active position the connection 74 is adjusted to permit of the shift of the element to dotted line position. The element 71 is of less width and length than the width and length of member 15.

The structure includes a closure member or 40 top 75 for the case. The member 75 comprises a rectangular body part 76 formed with means at each end, as at 77 for overlapping the members 18, 19 and the outer corners of the members 16, 17. The member 75 is provided with a hand-grip 45 78 and is releasably connected to the members 16, 17. For releasably connecting the member 75 to the members 16, 17 these latter are provided on their outer faces with spaced latches 79 which 50 coact with spaced keepers 80 anchored to the side edges of body part 76.

What I claim is:

1. In a convertible suit case and sectional table structure, a first member providing the bottom of the suit case and central section for the table top, a pair of foldable and extendible members hinged to the sides of the first member and providing when folded the sides of the suit case and when extended hinged outer sections for completing the table top, a second pair of foldable and extendible members hinged to the ends of the first member and providing when folded the ends of the suit case, a pair of oppositely disposed foldable and extendible legs, one pivotally connected at one end with one end of the first member 55 and the other pivotally connected at one end with the other end of the first member, said legs when extended providing supports for the table top and when folded encompassing said pairs of members for retaining these latter in folded relation, and the said second pair of members when extended providing fillers for a portion of the length of said legs.

2. In a convertible suit case and a sectional table structure, a first member providing the bottom of the suit case and the central section

of the table top, two pairs of foldable and extendible members hinged to and coacting with the first member to provide, when folded the body of the suit case, one of the pairs of members, when extended, coacting with the first member to complete the table top, a pair of oppositely disposed foldable and extendible legs, one pivotally connected at one end with one end of the first member and the other pivotally connected at one end with the other end of the first member, said legs 10 when extended providing supports for the table top and when folded encompassing the said pairs of members for retaining these latter in suit case body forming position.

3. In a convertible suit case and sectional table structure, a first member providing the bottom of the suit case and central section for the table top, a pair of foldable and extendible members hinged to the sides of the first member and providing when folded the sides of the suit case 20 and when extended hinged outer sections for completing the table top, a second pair of foldable and extendible members hinged to the ends of the first member and provided when folded the ends of the suit case, a pair of oppositely disposed foldable and extendible legs, one pivotally connected at one end with one end of the first member and the other pivotally connected at one end with the other end of the first member, said legs when extended providing supports for 30 the table top and when folded encompassing said pairs of members for retaining these latter in folded relation, the said second pair of members when extended providing fillers for a portion of the length of said legs, an adjustable 35 bracing element carried by the first member for the first pair of members when these latter are in position to complete the table top, and means for latching said legs and second pair of members together when the legs are in encompassing 40 relation with respect to said pairs of members.

4. In a convertible suit case and a sectional table structure, a first member providing the bottom of the suit case and the central section of the table top, two pairs of foldable and extendible members hinged to and coacting with the first member to provide when folded the body of the suit case, one of the pairs of members, when extended, coacting with the first member to complete the table top, a pair of oppositely disposed foldable and extendible legs, one 45 pivotally connected at one end with one end of the first member and the other pivotally connected at one end with the other end of the first member, one of said legs being formed with 55 means intermediate its ends for slidably connecting the legs together, said legs when extended providing supports for the table top and when folded encompassing the said pairs of members for retaining these latter in suit case body 60 forming position, a closure for the suit case body, the first pair of members and said closure having coacting means for latching them together, and the second pair of members being formed with means for latching the other ends of the legs 65 thereto for maintaining the legs in encompassing relation with respect to the pairs of members.

5. In a convertible suit case and a sectional table structure, a first member providing the bottom of the suit case and the central section of the table top, two pairs of foldable and extendible members hinged to and coacting with the first member to provide, when folded the body of the suit case, one of the pairs of members, when extended coacting with the first member to com- 75

plete the table top, a pair of oppositely disposed foldable and extendible legs, one pivotally connected at one end with one end of the first member and the other pivotally connected at one end with the other end of the first member, said legs when extended providing supports for the table top and when folded encompassing the said pairs of members for retaining these latter in suit case body forming position, an adjustable element of

pivottally suspended from the first member for positioning under the first pair of members for bracing them when they are positioned to complete the table top in connection with the first member, and means carried by one of the pairs of members for latching thereto the legs when folded.

ROBERT L. HESTES.
